UNITED STATES PATENT OFFICE.

WILLIAM W. STEWART, OF MUSCATINE, IOWA.

IRONING-BOARD.

1,137,172.

Specification of Letters Patent.

Patented Apr. 27, 1915.

Application filed March 24, 1813. Serial No. 756,573.

To all whom it may concern:

Be it known that I, WILLIAM W. STEWART, a citizen of the United States, residing at Muscatine, in the county of Muscatine and State of Iowa, have invented certain new and useful Improvements in Ironing-Boards; and I hereby declare that the following is a full, clear, and exact description thereof, reference being had to the accompanying drawings, which form part of this specification.

This invention is a novel improvement in ironing boards of that class which can be readily connected to a table or wall in convenient position for use, and detached and stowed away when not in use.

The invention consists in the novel means illustrated in the accompanying drawing for detachably attaching such an ironing board to the wall or to a table or other piece of furniture in the room in which it is desired to use the ironing board.

In said drawings—Figure 1 is a top plan view of the ironing board and support in position for use. Fig. 2 is a side view of such board in position for use, and showing the support in section. Fig. 3 is a detail view of the support detached. Fig. 4 is an enlarged detail section on the line Y—Y, 30 Fig. 2.

The ironing board A may be of any suitable make and width, and is provided with a supporting leg L which is preferably connected to the board by hinges J. A transverse piece K may be attached to the upper end of the leg as shown. The opening movement of the leg may be limited by means of a toggle lever composed of links D, E, pivotally connected together at H, and respectively pivoted at F to the board and at G to the leg. The connection is such that when the toggle is distended the pivot H can drop slightly past the line drawn between the pivots F, G, as indicated in Fig. 2, and lock the leg in vertical position.

To the opposite edges of the board, and at one end thereof, are attached spring plates B, by means of suitable screws, which plates project beyond the adjacent end of the board and have their outer ends bent to form beveled catches b which face each other. Those catches b are adapted to be engaged with a support attached to the wall, or to a table

or other piece of furniture. As shown this support consists of a long U-shaped bar having its ends attached to the wall by screws or nails as indicated at c, and provided near its ends with rectangular openings or slots c' which are adapted to be engaged by the catches b. These catches can be engaged with said slots c' by simply pushing the end of the board toward and against the support C, the catches b entering the slots c', being forced apart as they enter such slots; and after they pass the slots they spring in behind the front bar of the support, as indicated in Fig. 1, thus securely locking the board to the said support against both lateral and longitudinal movement; and when the leg L is adjusted to the position shown in Fig. 2 the board will be firmly and steadily supported in position for use. By having a plurality of supports C secured at different places, the board can be easily set up for use at any of such places.

When it is desired to remove the board the catches b can be forced apart by simultaneously pressing them outwardly so as to enable them to be withdrawn from the support through the slots c'; and the board can then be folded and stored.

I claim:

1. The combination with an ironing board of an apertured supporting member, means for attaching said board to said supporting member including oppositely facing spring members attached to and projecting beyond the ends of the board, and having oppositely facing beveled catches on their ends adapted to be simultaneously first sprung apart upon engagement of the beveled catch with the apertured supporting member and then to return to normal position to detachably lock the board in place substantially as described.

2. The combination with an ironing board, of an apertured supporting member, resilient members attached to and projecting beyond the end of the board, and adapted to be first sprung apart upon engagement with the apertured support and then to return to normal position to detachably lock the board in place, substantially as described.

WM. W. STEWART.
